[57] **CLAIM**

The ornamental design for an insertion tool for an animal identification tag, substantially as shown and described.

DESCRIPTION

FIG. 1 is a perspective view of an insertion tool for an animal identification tag or the like, showing our new design;

FIG. 2 is a rear elevational view;

FIG. 3 is a top plan view;

FIG. 4 is a bottom plan view;

FIG. 5 is an enlarged scale end elevational view taken along line 5—5 of FIG. 2;

FIG. 6 is an enlarged scale cross-sectional view taken along line 6—6 of FIG. 2; and

FIG. 7 is an enlarged scale cross-sectional view taken along line 7—7 of FIG. 2.

FIG. 1

FIG. 2

FIG. 3

FIG. 4

FIG. 5

FIG. 6
